CLAIM

I claim the ornamental design for a kite, as shown and described herein.

DESCRIPTION

FIG. 1 is a front perspective view for a kite showing my design;

FIG. 2 is a right side elevational view thereof, the left side being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is a front perspective view of a second embodiment of FIG. 1;

FIG. 8 is a right side elevational view of FIG. 7, the left side being a mirror image;

FIG. 9 is a front elevational view of FIG. 7;

FIG. 10 is a rear elevational view of FIG. 7;

FIG. 11 is a top plan view of FIG. 7;

FIG. 12 is a bottom plan view of FIG. 7;

FIG. 13 is a front perspective view of a third embodiment of FIG. 1;

FIG. 14 is a right side elevational view of FIG. 13, the left side being a mirror image;

FIG. 15 is front elevational view of FIG. 13;

FIG. 16 is a rear elevational view of FIG. 13;

FIG. 17 is a top plan view of FIG. 13; and,

FIG. 18 is a bottom plan view of FIG. 13.
